(57) **CLAIM**

The design for an orbital infant exerciser, as shown and described.

DESCRIPTION

FIG. 1 is a side perspective view of our new orbital infant exerciser;

FIG. 2 is a top plan view thereof;

FIG. 3 is a side elevational view thereof, with the opposite side being a mirror image;

FIG. 4 is a front elevational view thereof; and,

FIG. 5 is a rear elevational view thereof.
